tennial Cotton Gin Co., Columbus, Ga., a cor-
poration of Georgia

Application June 2, 1936, Serial No. 83,142

4 Claims. (Cl. 100—28)

This invention relates to improvements in presses of the type employed for baling cotton, and is more particularly concerned with an arrangement by which the structures may be located at ground level, for example, and without requiring a large pit space or elevated platform.

One of the features of the present invention is the provision of a strong and rigid assembly comprising lower frame members and uprising structures thereon for comprising and supporting the doors and other parts of press box structures, such assembly being capable of rotation from filling to pressing positions about a vertical axis.

Another feature of the present invention is the provision of a press comprising a rigid fixed frame and standard means, with a strong assembly rotatable with respect to said standard means between filling and pressing positions and having thereon the door structures for the press box.

Another feature of the present invention is the provision, in a press, of a rotatable assembly consisting of a strong girder arrangement, and having stiff upstanding structures for supporting the girder arrangement against warping or twisting and being stiff in itself to provide rigid pivot means for the press box doors.

Still another feature of the present invention is the provision of press dogs capable of clearing operation during the tamping or filling period for avoiding damage to themselves and to the tamping means, and being capable of operation during the pressing period for withdrawing them from the baled material.

Still another feature of the present invention is the provision of an up-packing ram structure which is connected to and supported on the fixed frame structure of the press.

With these and other features as objects in view, as will appear in the course of the following specification and claims, an illustrative form of practicing the invention is set out on the accompanying drawings, in which:

Figure 1 is a side elevation of the press.

Figure 2 is an end elevation of the same with end support structures omitted for clearness.

Figure 3 is an upright transverse section, on an enlarged scale, substantially on line 3—3 of Fig. 1.

Figure 4 is a corresponding section substantially on line 4—4 of Fig. 1.

Figure 5 is a top plan view of the ram structure and its mounting, on an enlarged scale.

Figure 6 is a transverse sectional view of the

ram structure, substantially on line 6—6 of Fig. 1.

Figure 7 is a view, on a greatly enlarged scale, of a press dog and its mounting structure.

Figure 8 is a horizontal sectional view substantially on line 8—8 of Fig. 2, on an enlarged scale, showing the clamping devices for the doors.

In these drawings, the press comprises a pair of lower channel beams 10, 11 which are connected rigidly with an upstanding post 12 at the end adjacent the press ram, this post in turn being rigidly connected at the top to a pair of top channel members 13, 14. At the upright central axis of the press is provided a fixed column 15 (Figs. 1 and 3) which extends through an aperture in a bottom block 16 (Fig. 3) which fills the space between the two lower channels 10 and 11 and is received between the inwardly projecting flanges thereof, being held fixedly in position by the bolts 17. The column 15 is threaded at its ends. The lower end of the column receives a nut 18 which rests upon the upper surface of the block 16 and is pinned against rotation relative to the column 15; and the rigidity of the column 15 with respect to the block 16 is assured by a lower nut 19 which engages a lower surface provided on the block 16. It will be noted that the block 16 is recessed so that the end of the column 15 and its nut 19 do not extend below the lower faces of the channel members 10 and 11. The upper end of the column 15 extends between the two channel members 13 and 14 and passes through an aperture 20 of the head block 20 which is mounted on the upper flanges of the upper channels 13 and 14 and secured thereto by bolts 21. A nut 22 engages the upper threads of the column 15 and is adjusted to fit against the lower face of the head block 20, being secured in position by a locking screw 23. The top nut 24 on the column 15 engages the upper surface of the head block 20. Thus the column 15 operates as a support member for the ends of the girders 13, 14 which are adjacent the central axis of the press, and also serves for transmitting pressing strains from the upper members to the lower members and thus to the frame of the press ram, so that both the weight and pressing strains are transmitted entirely by parts comprised in the press itself.

At the filling end of the press, it is provided with a loading and tamping structure of known type which has been shown generally by the dotted lines LT, and rests upon a top angle-

iron 25 supported by a channel 26 which is connected at its bottom to a transverse channel member 101 which in turn is bolted to flanges of the lower channel, and connected by light angle members 27 with the transverse channel piece 28 secured to the lower flanges of the upper channels 13 and 14 (Figs. 1 and 3). These angle members 27 receive the hopper or loading box 29 and position it above the press boxes.

The bottom block 16 at its upper surface provides a support for anti-friction bearings 30 which support the lower rotatable casting member 31, which extends laterally and supports the pairs of longitudinal channel members 32, 33 having outwardly turned flanges. Transverse channels 32a, 33a are provided at each end of each press box, that is, at the ends of the longitudinally channels 32, 33 and near the centers thereof: the channels 32, 33 and 32a, 33a are connected together by tying angles (Figs. 2 and 3) which preferably are welded to the transverse channels and bolted to the longitudinal channels. On the top flange of the upper channel members 32, 33 are positioned the laterally extending platforms 34 which are formed of plate metal and are stiffened at their outer edges and ends, and at intermediate points, by the channels 35, 36. Braces 37 are connected to the channels 36 and extend inwardly and downwardly and are supported on, and secured to the webs of, the lower channels 33, thus providing a stiff strong support for the platforms 34. These structures, comprising the casting 31 and the other parts, are connected fixedly together to provide a rigid structure capable of supporting the weight of attendants on the platforms, and of receiving the weight of a bale of cotton or other packed material being discharged from the press.

The inner faces of the channels 32, 33 are lined by the plate metal facing pieces 38 which extend from the lower edges of these channels upwardly above the platforms 34, and then are bent outwardly and downwardly and connected to these platforms to provide a further stiffening thereof, and to assure that each press box shall have a fixed bottom portion extending above the platforms 34.

Fixedly mounted on the platforms 34 and secured thereto and to stiffeners 36 are provided the bottom door pivot blocks 40 which receive the upwardly extending door pivot rods 42. These rods are free at their upper ends and extend upwardly through transverse channel members 43, 44 (Figs. 1 and 3) which are apertured to receive the column 15. Each of these channel members 43, 44 is provided with a cast bushing 45 to which it is fixedly secured, and which in turn provides a mounting therefor on the column 15. The two bushings 45 are connected by a sleeve 46 of appropriate length, being fixed to this sleeve by the locking screws 47 so that the structure comprising the channels 43, the bushings 45, and the sleeve 46 rigidly support the door pivot rods 42 against change of proper vertical position.

The lower channel 44 rests upon the split sleeve 48 which is received in a reduced portion of the column 15 and is clamped tightly to the column 15 to provide a support for carrying a part of the weight of the press box doors.

The press comprises two press boxes, one of which is located below the loading and tamping structure LT, while the other is located above the press ram PR, as will be described herein-

after; these boxes being supported for rotation about the axis of column 15 and upon the anti-friction bearings 30 for interchangeability of these positions. Each press box comprises a pair of side doors SD and a pair of end doors ED.

The side doors comprise vertical planks in the usual way, these planks being spaced slightly apart at their upper ends for the reception of the press dogs and for observation of the course of 10 loading and pressing, and stiffened at their bottoms by angles 56x.

These planks are secured to the pairs of stiffener members 50 which are illustrated as channel irons, and apertured for fitting around the 15 corresponding pivot rod 42 for the respective door. For providing smooth pivot points, filler blocks 51 are located in the channels 43, 44; and these blocks are provided with clamping screws 52 which assure a proper positioning of the 20 channels with respect to the rods 42, and prevent movement of the doors up and down relative to the column 15. It will be noted that the rods 42 are themselves held in the door pivot blocks by screws 53. Thus, screws 52 bind 25 against rods 42 and keep the sleeve assembly 46 from raising when the ram ascends and screws 53 hold said rods 42 securely to blocks 40 on platform 34. The pairs of stiffener members 50 are preferably further supported by the turnbuckle brace members 54.

The end doors ED for each of the boxes are mounted for rocking movement about horizontal axes, each of these axes being provided by a pair 30 of hinge pieces 55 fixed to the door boards and pivoted with respect to the hinge pieces 56 which are connected to the cross members 32a (Figs. 2 and 3) joining the upper channels 32. These doors may swing outwardly at their tops, in opening the press boxes to release a bale, through 35 a limited distance determined by the engagement of the doors with the vertical members 12, 15 and 26. Their inward movement is limited by the construction of the hinges and the engagement of the door boards with the cross members 45 32a, so that they are ready for proper abutting relationship with the side doors, as will be described hereinafter in conjunction with Fig. 8. These end doors are likewise provided with the 40 stiffening channel members 50a at the horizontal planes of the corresponding side door stiffening members 50.

As stated above, the side doors SD are each provided with press dogs. As shown in Figs. 1, 2, 4 and 7, the side boards forming a door SD 55 are provided with fixed dog rod bearings 60 providing a mounting for a dog rod or shaft 61. Opposite each of the spaces between the door boards is mounted a press dog 62 which can extend through the corresponding crevice and into the press box. One of these dogs 62 has a bifurcated heel portion 62a with a pivot connection 63 to a link 64 which is connected by a pivot 65 to further links 66 which are mounted by a pivot pin 67 inside a housing block 68 having an outwardly presented wall 69 with an aperture 70 therein for receiving the stem 71 of an eye-bolt which engages around a pin 72 engaged with the links 66. The outer end of the eye-bolt 71 has a nut 73, locknut 73a and washer 74 for engaging a compression spring 75 which reacts against the wall 69. An adjusting screw 76 regulates the normal position of pin 67 which in turn regulates the relative positions of links 64 and 66 to each other. This adjustment affords 75 a means of regulating the pressure required by

the cotton against dogs 62 necessary to trip them from the full line position of Fig. 7 to the broken line position of Fig. 7. The housing block 68 is free for rotation in a clockwise direction about the axis of the rod 61 into the dotted line position of Fig. 7, while the dogs may rock in a counterclockwise direction with the rods 61 into the broken line position of Fig. 7, under the conditions described hereinafter, carrying with them the links into the position also shown in dashed lines and compressing the spring 75, so that this spring operates thereafter to return the dogs to the normal full line position.

The side doors SD and the outer end door ED of each box may be locked or clamped in position for filling or pressing by the use of ties, as shown in Figs. 1, 2 and 8. Two ties are used at the outer end of each box, and each of these ties comprises an eye-bolt 90 adjustable in a block 91 having a pivotal mounting 91a between the corresponding pairs of side door stiffener members 59. The eye-bolt receives a link piece 92 having a slotted end 92a which fits (Fig. 8) around the pin 93 of the cam piece 94. This cam piece 94 is secured on the vertical shaft 95 which has a worm wheel 96 operated by a worm which may be rotated by the hand wheel 98. The slotted end link piece 92 may be easily engaged with or disengaged from the pin 93 when the latter is in the dotted line position of Fig. 8; and rotation of the shaft 95 in a counterclockwise direction (Fig. 8) will cause the pin to draw the link piece 92 into position and to produce a tension effect in the eye-bolt 90, so that the side doors SD are drawn tightly against the end doors ED. It will be noted that the stiffening channels 59a of the outer end door ED extend past the lateral edges of the boards for this door and furnish an abutment for the lateral edges of the boards of the side doors SD, and further that the blocks 91 operate, when the eye-bolts 90 are under tension, to press the members 59a and therewith the rest of the end door structure inward, and operate during filling, tamping and pressing to prevent outward movement of this end door at the corresponding corners. At the corner adjacent the shaft 95, the side door stiffener members 59 are provided with the stop and wedging members 91b which correspondingly engage the stiffening members 59a to prevent outward movement of the end door ED during filling, tamping and pressing, and have inclined surfaces to assure a proper engagement of the side and end doors for forming the press box. At the inner end of the press box, the end door ED similarly has reinforcing members 59a to support the vertical boards thereof; and these members 59a likewise extend for abutting relation with the lateral edges of the boards of the side doors SD. Wedging blocks 91c are provided on the stiffener members 59 and have curved wedging surfaces for engagement with the end door stiffening members 59a when the side doors are swung closed, so that they operate for bringing the door edges into proper abutting relationship (Fig. 8) and maintaining them therein against internal pressure of the press box. It will be noted that the four doors of each press box are thus secured in rectangular form at the horizontal planes constituted by the stiffening members 59, 59a by the utilization of the tying means and the wedging devices; and since this effect is produced at spaced points along the height of the box, a very tight assembly is effected.

Since the press box which has just been loaded from the loading and tamping device LT is heavier than the press which has just been emptied of a pressed and tied bale, it is preferred to provide the lower structure of the rotatable assembly with a roller 100 which rests upon a support 101 connected to the lower channels 10, 11; and, similarly, to prevent rising of the opposite end of the press by providing a shelf 102 above the corresponding roller 100. At each end of the press, also, is provided a locking bracket 103 having a notch therein for receiving the locking pawl 104 controlled by a locking lever 105 in order to assure that the boxes are retained in proper position beneath the loading and tamping device LT and above the press ram PR, so that no damage may be done to such structures by accidental swinging of the rotatable assembly.

The press ram PR is shown in Figs. 4, 5 and 6 as comprising the lower block member 110 having laterally rising wall portions for receiving the bolts 111 which fasten the block in position between the lower channels 10, 11, and resting on the lower flanges of these channels. This security of the parts is further assured by the tie bolt and collar devices 112 which extend through the channels 10, 11 and thus secure the same against spreading opposite the ram PR. The ram structure further includes a head and gland structure 113, and the top or press plate 114 of the ram proper. The ram may be operated, as usual, by hydraulic means; and includes also the cylinder 115 (Fig. 4) and the piston 116 therein. It will be noted that this arrangement requires merely the excavation of a small hole deep enough to receive the cylinder and associated conduits, and that this hole may be lined by terra cotta pipe 117.

Since the press is of the up-packing type, a follower block 120 is provided which is comprised of spaced channels having their edges directed downwardly and resting upon the top flanges of I-beams 121 which are tied together by clamping bolts and collars 122. The channels 120 forming the block are spaced apart to facilitate the proper insertion of the bale ties, and in the lower position of the ram (Fig. 4) rest upon supporting angles 123 secured to the lower portions of the rotatable assembly.

The pressure of the cotton is sustained by similar channel members 125 secured to the lower flanges of the top channel girders 13, 14 (Fig. 4), these channels 125 being similarly spaced to facilitate the insertion of the bale ties.

In operation, with the parts in the position shown in Fig. 1, cotton is delivered into the right-hand press box which is now closed and clamped. As the tampers move downwardly in pressing the cotton during the loading operation, they can easily pass the press dogs 62 as the latter turn in a clockwise direction while rocking the corresponding housing 68. When the press box has been tamped to the desired fullness with cotton, the loading and tamping structure LT is raised and removed from the press box in the usual way. During its upward movement, the press dogs 62 yield, if necessary, by moving the links into the dashed line position and with compression of the spring 75.

The latch lever 105 is actuated and the press boxes are rotated about the axis of the column 15 so that the empty box is brought beneath the loading and tamping structure LT while the filled box is brought above the ram PR. The press dogs operate during this time for holding the

cotton against bulging from the loaded press box. It will be noted that these dogs have an inward and downward curvature, facilitating this action.

The press ram PR is now energized and its top pressure plate 114 moves upwardly and engages the bottom faces of the I-beams 121, so that the follower block is raised and the cotton is forced upwardly, this movement being resisted by the head block 125. The cotton is thus compressed to the desired degree, the dogs 62 yielding upwardly and outwardly as the cotton is compressed and raised beneath them, and finally are practically squeezed out of the bale being formed.

When the cotton has been compressed to the desired extent, the handwheel 98 for the corresponding press box is backed off, and the doors are released. The end doors are permitted to move outwardly about their lower hinges while the side doors are swung open about the pivot rods 42. The bale ties are now inserted and clinched to secure the bale. The press ram PR is released and permitted to move downward, the follower block and bale operating to force it downward. When the follower block comes to the level of the upper edge of the plates 38, the movement of the press ram PR is stopped and the bale is pushed from this plate and usually immediately off the platform 34, and is removed from the vicinity of the press in the usual way. It will be noted that in a one story up-packing press of this type, the bale has but a small distance to drop in passing from the level of the follower block to the platform and thence to the ground, as the structure can be mounted above the pit lined by the tile 117, by the employment of a relatively narrow trench 130 which may be lined with concrete, if so desired, and serves to receive the channel girders 10, 11 below the floor level. Thus the structure is extremely compact and requires relatively small building space for equipment of large capacity.

Figures 3 and 4 have been broken away to indicate the pertinent portions of the structures involved, but it will be understood that the end and side doors and other portions may be of any desired length for the formation of bales of the required dimensions.

The structure provided is strong and rigid, and requires little excavation and only sufficient space above the top girder structure 13 for receiving the loading and tamping devices, and hence the assembly is known as a "one story up-packing press." The column 15 with the top block 20 and bottom block 16 and the standard 12 connect the top girder structure and the bottom girder or base structure rigidly together for resisting relative vertical movements of these parts even under the circumstances incident to the operation of the ram; while the rotatable structure, comprising the bottom girders and stiffening members, provides a firm support for the door structures in conjunction with the parts which are held in proper spaced and vertical relationship by their association with the column 15, as shown in Fig. 3, even under the circumstances of pressing and under the circumstances arising in rotating a filled press box from the loading position into the pressing position.

It is obvious that many changes may be made in the structure without departing from the scope of the appended claims.

We claim:

1. A one story press having a lower platform structure including superposed channel members at opposite sides thereof, a floor below the plat-

form structure having a countersink, a ram head mounted in the countersink, a follower slidably mounted within the platform structure in alignment with the ram head, vertically extending rods mounted directly on the platform structure, a bale chamber above the platform structure having doors perpendicular to the platform structure and extending throughout the height of the baling chamber, said doors being pivoted on said rods, means providing a vertical axis laterally of the bale chamber upon which the platform is movable horizontally, linings disposed against the inner surfaces of said channel members and projecting above the platform structure folded over and secured to the latter for reinforcement thereof and to provide fixed portions adjacent the bottom of the bale chamber, the inner surface of said lining being in alignment with the adjacent inner wall surface of the bale chamber, a tamper laterally positioned with respect to the ram head for movement into the bale chamber, the distance between the level of the platform structure and the floor level being less than the distance between the inner surfaces of said doors.

2. A press having a platform structure, a ram means, a tamper means, a bale chamber above the platform structure for coaction with the ram means and the tamper means, a column providing a vertical axis laterally of the bale chamber upon which the platform is movable horizontally, said chamber having doors perpendicular to the platform structure, vertically positioned rods for supporting the doors, said rods having their lower ends directly secured to the platform structure and having their upper ends free, and means surrounding the vertical column and connected to said rods.

3. A press having a platform structure, a ram means, a tamper means, a bale chamber above the platform structure for coaction with the ram means and the tamper means, a column providing a vertical axis laterally of the bale chamber upon which the platform is movable horizontally, said chamber having doors perpendicular to the platform structure, vertically positioned rods for supporting the doors, said rods having their lower ends directly secured to the platform structure and having their upper ends free, vertically spaced apart upper and lower members surrounding said column, means connecting said upper and lower members together adjacent said column, means on the column directly engaging and supporting the lower member, and pairs of spaced stiffening members on the doors between which the upper and lower members extend having openings through which said rods pass.

4. A press having a platform structure, a ram means, a tamper means, a bale chamber above the platform structure for coaction with the ram means and the tamper means, a column providing a vertical axis laterally of the bale chamber upon which the platform is movable horizontally, said chamber having doors perpendicular to the platform structure, vertically positioned rods for supporting the doors, said rods having their lower ends directly secured to the platform structure and having their upper ends free, vertically spaced apart upper and lower members surrounding said column, means connecting said upper and lower members together adjacent said column, means on the column directly engaging and supporting the lower member, said upper and lower members being directly connected to said rods.

GEO. G. SMITH.

HUGH ROBERTS, JR.
